ROD BUNDLE TRANSFER DEVICE

Peter S. Wick, Duluth, Minn., assignor to The American Steel and Wire Company of New Jersey, a corporation of New Jersey

Application June 8, 1939, Serial No. 278,139

2 Claims. (Cl. 198—20)

This invention relates to the handling of hot coiled rod and, more particularly to rod bundle transfer devices which operate to move a rod bundle having its central aperture extending 5 vertically into a right-angular position.

In the manufacture of rod, the rolling mill, hereinafter referred to as the rod mill, is provided with a device which coils the rod into bundles and delivers it horizontally over a bed 10 with its axis extending vertically. The delivery means is in the form of a floor level intermittently operating drag conveyor. From this last named instrumentality, it is desired to transfer the rod bundles to a continuously operating hook 15 conveyor for further cooling, inspection, trimming, and subsequent processing. The essential point in the transfer of the rod bundle from one conveyor to the other is that the top of the bundle as it lays on the intermittently operating drag 20 conveyor, which is the last end rolled in the mill, must be placed facing outwardly on the continuously operating hook conveyor.

It is among the objects of the present invention to transfer a rod bundle having its central 25 aperture extending vertically into a right-angular position by moving it in such manner that what was formerly the top of the rod bundle becomes the trailing end thereof when moved into right-angular position.

Another object is the provision of a device of 30 the class described which is cheap and easy to manufacture and operate.

The foregoing and other objects will be apparent after referring to the drawings, in which:

Figure 1 is a plan of the apparatus of the invention;

Figure 2 is a side elevation;

Figure 3 is a fragmentary side elevation of a portion of the apparatus of Figure 2 in a modified position;

Figure 4 is a view on the line IV—IV of Figure 2; and,

Figure 5 is a fragmentary side elevation illustrating a modification.

Referring more particularly to the drawings, the numeral 2 designates the bed of an intermittently operating drag conveyor. This bed 2 is provided with a longitudinal slot 3 through which drag hooks 4 project. These drag hooks 4 are driven in a suitable manner (not shown) and embody elongated portions which are adapted to extend vertically through the centers of the rod bundles being conveyed.

Adjacent the terminus of operation of the drag conveyor, the elongated portions 5 of the drag

hooks 4 are withdrawn from the longitudinal slot 3 in the bed 2. At this end of the drag conveyor, extending in the same direction as the longitudinal slot 3 in the bed 2, and on either side thereof, is a slot 10. Immediately beneath 5 each of the slots 10 is a horizontally pivoted arm 12 adapted to move through the slot and in an arc toward the rod mill. The slots 10 and, accordingly, the arms 12 are closer together than the diameter of the rod bundles, and the bundles 10 are adapted to be raised thereby in an arc with the top portions thereof moving toward the rod mill.

Immediately beneath the parallel arms 12 there is disposed an electric motor 15 having a conventional magnetic brake 16. The drive shaft of the motor 15 is connected to the driving shaft of an adjacently disposed speed reducer 18. At each end of the driven shaft of the speed reducer 18 there is secured a crank 20. Each of the cranks 20 is pivotally connected to a connecting rod 22.

The pivots, hereinafter designated 24, for the parallel arms 12, carry bell crank levers 25 which are shown in the full-line position of Figure 2 as having short horizontal portions 25^a and long 25 downwardly depending portions 25^b.

Referring particularly to Figure 1, each of the arms 12 is provided with a short longitudinally extending slot 27. Beneath each of the slots 27 there is disposed a dog 29 comprising a V-shaped 30 lever having one of its ends pivoted to the adjacent arm 12 and its free end 33 disposed for movement through the slot 27. These dogs 29 are more clearly shown in Figure 2.

The long downwardly depending portions 25^b of 35 the bell crank levers 25 are adapted to engage, and accordingly raise and lower, the arms 12 through the operation of the electric motor 15.

The pivoted side of each of the dogs 29 is provided with a slot 31 and the downwardly depending portion 25^b of the adjacent bell crank lever 25 carries a pin 32 which rides in the slot. This permits the protrusion of the free ends 33 of the dogs 29 through the slots 27 in the arms 12. Thus the rod bundle is not only lifted by the arms 12 40 and moved in an arc, but it is prevented from sliding off the arms 12 by means of the free ends 33 of the dogs 29.

As shown in Figure 2, a continuously operating hook conveyor is disposed to have its hooks 50 move at approximate right-angles with respect to the direction of movement of the intermittently operating hook conveyor. This hook conveyor is provided with a number of hooks 35 which extend toward the drag conveyor.

It is among the teachings of the invention to move the raised rod bundle from the dotted-line position of Figure 2 onto one of the hooks 35 of the hook conveyor and thus dispose the trailing end of the rod bundle on the outer side thereof. Accordingly, there is provided the following construction and arrangement of instrumentalities:

Along either side of the bed 2 there is disposed a longitudinally extending track 36 having upwardly extending ends or stops 37.

A four-wheeled carriage 39 is disposed on, and adapted for movement along, the tracks 36. The four-wheeled carriage 39 is so constructed, and the distance between the tracks 36 such, that the hooks 4 of the intermittently operating drag conveyor and the rod bundles carried thereby are freely moved under said carriage toward the continuously operating hook conveyor.

The four-wheeled carriage 39 carries a pair of longitudinally extending tracks 41 upon which there is mounted a four-wheeled carriage 43. The four-wheeled carriage 39 carries a pair of resilient buffers 45, while the four-wheeled carriage 43 carries a cooperating pair of strike plates 47, whereby the movement of the last named carriage away from the rod bundle lifting arms 12 is limited.

Reciprocating motion is given the upper four-wheeled carriage 43 by an electric motor 50 which is disposed beneath the lower four-wheeled carriage 39. This electric motor 50 is provided with a conventional magnetic brake 51. The drive shaft of the motor 50 is connected to the driving shaft of an adjacently disposed speed reducer 53. At one end of the driven shaft of the speed reducer 53 there is secured a crank 54 which is pivotally connected to a connecting rod 55.

Immediately above the outer end of the connecting rod 55 there is disposed a substantially vertically extending lever 57 which is pivoted intermediate its ends, as shown at 58.

The lower end of the lever 57 is short and is pivotally connected, as shown at 60, to the outer end of the adjacent connecting rod 55. The upper end of the lever 57 is long and is pivotally connected, as at 61, to a link 62 which is, in turn, pivotally connected, as at 63, to the adjacent end of the four-wheeled carriage 43.

As reciprocating motion is imparted to the four-wheeled carriage 43 by the electric motor 50, a like but lesser motion is transferred to the lower four-wheeled carriage 39 through the tracks 41 and buffer devices 45 and 47.

The upper four-wheeled carriage 43 carries an electric motor 65, the drive shaft of which is connected to the driving shaft of an adjacently disposed speed reducer 67. At one end of the driven shaft of the speed reducer 67 there is secured a crank 69, which is pivotally connected to a connecting rod 70.

The outer end of the connecting rod 70 is provided with a longitudinally extending slot 71 immediately adjacent which there is pivotally mounted a bell crank lever 73. The upper end of this bell crank lever 73 is bifurcated and provided with a pin 75 which rides in the slot 71 in the connecting rod 70. The lower end of the bell crank lever 73 is long and forms a prong 77 which is constructed and arranged to pick up rod bundles which have been elevated by the lifting arms 12 to the dotted-line position of Figure 2.

Referring to Figure 3 of the drawings, the end of the lower four-wheeled carriage which is most adjacent the continuously operating hook conveyor carries a pair of pivoted vertically extending upwardly converging bars 80 which terminate in an inverted loop 81. This inverted loop 81 straddles the prong 77 when the latter is in the dotted-line horizontal position of Figure 2.

One of the vertically extending upwardly converging bars 80 has a right-angular extension 83 at its pivotal mounting which is pivotally connected to a downwardly depending link 84. Beneath the right-angular extension 83 on the lower end of one of the vertically extending upwardly converging bars 80 there is disposed a substantially horizontally extending lever 85 which is pivotally mounted intermediate its ends, as shown at 86. One end of the horizontally extending lever 85 is pivotally connected to the lower end of the adjacent downwardly depending link 84. The other end of the substantially horizontally extending lever 85 depends downwardly to a slight extent and thereby is enabled to make contact with a roller 87 on the adjacent upwardly extending end 37 of the tracks 36.

In Figure 5 of the drawings, I have disclosed a modified form of apparatus of the invention. According to this embodiment, there is a pair of widely spaced cam plates 120 beside one of the tracks 36. The lower four-wheeled carriage 39 carries a pivoted follower 122 to which there is connected a pair of vertically extending upwardly divergent rods 124. Each of the rods 124 is connected to a pawl 126 which, together, serve to lock the bumper devices 45 and 47 on the return movement of the lower four-wheeled carriage 39 and the wheels of the upper four-wheeled carriage 43 against the end of the tracks 41. This prevents inertia of the lower four-wheeled carriage 39 from separating it from its relative position with the upper four-wheeled carriage 43 when the latter is decelerating at the ends of its motion.

In operation:

A rod bundle is delivered by one of the hooks 4 of the intermittently operating drag conveyor to the position designated at A in Figures 1 and 2, at which point it rests on the bed 2 of the drag conveyor and the rod bundle lifting arms 12. The operation of the electric motor 15 is initiated in any suitable manner, whereupon the cranks 20 are caused to make one complete revolution, on completion of which the magnetic brake 16 is applied. This limited rotation of the cranks 20 is controlled by a limit switch 90 which is operated thereby. The rotation of the cranks 20 acting through the connecting rods 22 and the bell crank levers 25 first causes the dogs 29 to move to the position designated in dotted-lines at B in Figure 2. While in this position the free ends 33 of the dogs 29 are behind the rod bundle. At this time, the downwardly depending portions 25b of the bell crank levers 25 are raised into contact with the rod bundle lifting arms 12, causing the outer ends of the latter to rise and thereby form an increasing inclined thereupon. The rod bundle will slide backwardly until it is resting against the free ends 33 of the dogs 29, whereby the rod bundle is carried to the position designated at C in Figure 2, thus relatively inserting the prong 77 in the position shown in full lines in Figure 2.

At this point of operation, an interlock between the limit switch 90 and a limit switch 91 which is operated by the driven shaft of the speed reducer 67, initiates the operation of the electrical motor 65. This causes the prong 77 to be elevated to the horizontal dotted-line position D shown in Figure 2. At this point, the limit switch 91 stops the motor 65.

As the rod bundle is raised from the position C by the prong 77, the rod bundle lifting arms 12 will continue in their cycle and recede downwardly from their uppermost position to their original horizontal position. The free ends 33 of the dogs 29 then recede to rest in a position shown in full lines in Figure 2.

The operator then closes a manual switch when an empty hook 35 of the continuously operating hook conveyor reaches a predetermined position. At this point, there is operated in any suitable manner (not shown) the electric motor 50, which, through the connections referred to hereinbefore, advances the upper four-wheeled carriage 43, thereby moving the prong 77 from the horizontal position D shown in Figure 2 to the horizontal position F of the same figure, thus relatively inserting the hook 35 into the rod bundle. In the meanwhile, the roller 87 on the upwardly extending portion 37 of the track 36 engages the slightly downwardly depending portion of the lever 85 which actuates the vertically extending upwardly converging rods 80 and the inverted loop 81 connecting the same to act as a stripper bar to hold the rod bundle in the position G of Figure 3 while the prong 77 is withdrawn. During this time, the electric motor 50 continues to run, driving the crank 54 past dead center, causing the upper four-wheeled carriage 43 to recede and carry with it the prong 77. This relative motion of the upper four-wheeled carriage 43 with respect to the lower four-wheeled carriage 39 withdraws the prong 77 while the rods 80 and inverted connecting loop 81 remain fixed, thus dropping the rod bundle onto the hook 35 in the position designated at G in Figure 3.

The bumper devices 45 and 47 are now in contact and the continued motion of the upper four-wheeled carriage 43 moves the lower four-wheeled carriage 39 from the position shown in full lines in Figure 3 to the position shown in full lines in Figure 2. The lever 85, being relieved of the roller 87 on the upwardly extending end of the track 36, permits the rods 80 and inverted connecting loop 81 to be returned to the position shown in Figure 2 by means of a suitable counterweight 105.

The upper four-wheeled carriage 43, now in its rearward position, advances relative to the lower four-wheeled carriage 39. At this time, a magnetic brake 51 stops the motor 50 and brings the upper four-wheeled carriage 43 to rest with its wheels in contact with the adjacent (left-handed) upwardly extending ends 37 of the tracks 36 (see Figure 2). An interlock of a limit switch 106 on the driving shaft of the speed reducer 53 with the limit switch 91 starts the motor 50 to return the prong 77 to its starting position. This completes the cycle of operation.

While I have shown and described one specific

embodiment of my invention and a modification thereof, it will be understood that these embodiments are merely for the purpose of illustration and description and that various other forms may be devised within the scope of my invention, as defined in the appended claims.

I claim:

1. Conveying apparatus for rod bundles comprising, in combination, a conveyor adapted to move the rod bundles in a substantially horizontal path with the axes thereof substantially vertical, a conveyor adapted to move said rod bundles in a path at substantial right angles with respect to the path of said first-named conveyor and with the axes thereof substantially horizontal, and intermediately disposed means adapted to elevate said rod bundles from said first-named conveyor in an arcuate path with the upper convolutions of said bundles away from said second-named conveyor, said means being constructed and arranged to support said rod bundles with their axes substantially horizontal and to transfer the same onto said second-named conveyor, said means including a reciprocable truck carrying a horizontally pivoted prong for supporting the rod bundles, means for elevating and lowering said prong, means for stripping the rod bundles from said prong onto said second-named conveyor, and means for imparting reciprocatory movement to said reciprocable truck.

2. Conveying apparatus for rod bundles comprising, in combination, a conveyor adapted to move the rod bundles in a substantially horizontal path with the axes thereof substantially vertical, a conveyor adapted to move said rod bundles in a path at substantial right angles with respect to the path of said first-named conveyor and with the axes thereof substantially horizontal, and intermediately disposed means adapted to elevate said rod bundles from said first-named conveyor in an arcuate path with the upper convolutions of said bundles away from said second-named conveyor, said means being constructed and arranged to support said rod bundles with their axes substantially horizontal and to transfer the same onto said second-named conveyor, said means including a reciprocable truck carrying a horizontally pivoted prong for supporting the rod bundles, means for elevating and lowering said prong, means for stripping the rod bundles from said prong onto said second-named conveyor, a second reciprocable truck for supporting said first-named reciprocable truck, a driving connection between said first-named reciprocable truck and said second-named reciprocable truck, and means for imparting reciprocatory movement to said first-named reciprocable truck.

PETER S. WICK. 60
